(57) **CLAIM**

The ornamental design for the notebook computer, as shown and described.

DESCRIPTION

FIG. 1 is a perspective view of the notebook computer, wherein the display is in an unfolded state;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

FIG. 8 is a perspective view of the notebook computer, wherein the display is in a folded state;

FIG. 9 is a front view thereof;

FIG. 10 is a rear view thereof;

FIG. 11 is a left side view thereof;

FIG. 12 is a right side view thereof;

FIG. 13 is a top view thereof; and

FIG. 14 is a bottom view thereof; and,

FIG. 15 is a perspective view of the notebook computer, wherein the notebook computer and the display are both in a folded state.

The dash-dot broken lines shown in FIGS. 1-3, 6-10, and 13-15 form boundaries of the claimed design. The dashed broken lines, showing lettering and icons on the folding leaves of the notebook computer in FIG. 15, represent environment that forms no part of the claimed design. All other broken lines in FIGS. 1-15 represent portions of the design and form no part thereof.

1 Claim, 15 Drawing Sheets
